Oscar Geier

UNITED STATES PATENT OFFICE.

MICHAEL LUKACS, OF NEW YORK, N. Y., ASSIGNOR OF ONE-HALF TO DAVID GLÜCK, OF NEW BRUNSWICK, NEW JERSEY.

DEVICE FOR ATTACHING TIES.

1,242,216.

Specification of Letters Patent.

Patented Oct. 9, 1917.

Application filed December 18, 1916. Serial No. 137,589.

To all whom it may concern:

Be it known that I, MICHAEL LUKACS, a subject of the Emperor of Austria-Hungary, resident of New York, county of New York, and State of New York, have invented certain new and useful Improvements in Devices for Attaching Ties, of which the following is a specification.

This invention relates to improvements in necktie fasteners, and has as its principal object the provision of means whereby an element slidably engaged with the tie may be secured readily to a button of the common form and the tie afterward manipulated so as to bring it into proper relation with the collar or other neckwear of the wearer.

Another object is to provide such fasteners comprised of few and simple parts, the same being readily engageable or disengageable and which in no wise affect the appearance of the tie.

These and other like objects are attained by the novel construction and combination of parts hereafter described and shown in the accompanying drawing, forming a material part of this disclosure, and in which:

Figure 1 is a rear plan view of a tie showing the application of the fastener.

Fig. 2 is a similar rear plan view, parts being broken away to show the application more clearly.

Fig. 3 is a rear plan view of the fastener drawn to an enlarged scale.

Fig. 4 is a front view of the same, and

Fig. 5 is a vertical sectional view taken on line 5—5 of Fig. 4.

The tie, here designated by the numeral 10, is of the ordinary construction, provided with an encircling band 11 near the top, from the upper rear portion of which extend wing elements 12 adapted to be inserted between the down-turned portions of an ordinary collar in the usual manner.

Rigidly secured by the arms 15 by stitching or like means to the back of the tie, is a plate 16 to which is attached a casing 17 having a raised central portion 18 presenting a longitudinal recess 20 in which is slidably engaged a flat bar 22 having at one

end a reentrantly turned extension 23 adapted to entirely fill the space between the plate 16 and raised portion 18 of the casing.

Formed in the bar 22 are two indentations, respectively 25 and 26, engageable with which is a projection 28 formed near the end of a resilient tongue 29 integral with the plate 16.

Formed in the raised cover 18 of the recess 20 is a transverse indentation 30 the point of which is engageable with the indentations 25 and 26 whereby the bar may be resiliently held in either of its adjusted positions.

At the lower end of the bar 22 is a circular head 32 having a recess 33 encompassing the center of the circle, and engaged with the raised marginal edges 35 of the head, by means of integrally formed clips 36, is a resilient spring element 38 having closely approaching curved ends 39 which are pressed apart as the button stem is entered into the opening 33 engaging the stem in the manner of a spring clip whereby the circular end of the bar is resiliently but securely attached to the stem of the button.

This is preferably done when the bar 22 is in its upper position, being afterward drawn down as shown in Figs. 3 and 4, whereby the tab elements 12 are raised into proper relation with the collar.

Having thus described my invention, what I claim as new, and desire to secure by Letters Patent, is:

1. A necktie fastener comprising a plate attached to the tie, a bar slidably engaged with said plate, means for holding said bar in two different positions, an eye formed at the bottom of said bar, and means combined with said eye for resiliently engaging the shank of a button.

2. A necktie fastener comprising a plate, means for attachment to the tie, a casing on said plate, a bar slidably engaged within said casing, said bar having spaced indentations, a spring formed with said plate engageable with either of said indentations, an open eye formed with said bar, and a resilient clip engaged with said eye partially inclosing the opening thereto.

3. A necktie fastener comprising a casing adapted to be secured to the back of a tie, a slidable bar engaged within said casing, means for maintaining said slidable bar in an adjusted position, a circular head formed with said bar, said head containing a slot encompassing the center, a double

pointed resilient clip partially surrounding said head having its free ends partially obstructing said slot, and means for securing 10 said clip to said head.

In testimony whereof I have affixed my signature this 7th day of December, 1916.

MICHAEL LUKACS.
